UNITED STATES PATENT OFFICE.

LÉON NICOLAS BRILLOUIN, OF PARIS, AND GEORGES ARMAND BEAUV AIS, OF CALUIRE, LYON, FRANCE.

TELEPHONE AND WIRELESS-TELEGRAPHY INSTALLATION.

1,405,267.

Specification of Letters Patent. Patented Jan. 31, 1922.

Original application filed June 13, 1917, Serial No. 174,633. Divided and this application filed June 10, 1918. Serial No. 239,244.

To all whom it may concern:

Be it known that we, LÉON NICOLAS BRILLOUIN and GEORGES ARMAND BEAUV AIS, both citizens of the French Republic, and residing 5 the first one at Paris, France, and the second one at Caluire, Lyon, Department of Rhône, France, have invented certain new and useful Improvements in Telephone and Wireless-Telegraphy Installations, (for which we 10 have filed applications in France, Nov. 7, 1916; Belgium, Feb. 2, 1917; Italy, Feb. 6, 1917; Russia, March 24, 1917, and April 6, 1917; England, Feb. 22, 1917,) of which the following is a specification.

15 The invention relates to telephone and wireless telegraphy installations, and it concerns more particularly installations of the kind described in the U. S. patent application S. N. 174,633, filed June 13, 1917, of 20 which the present application is a division, i. e. installations comprising, as amplifier, at their receiver stations, a certain number of audions having each a filament heated by an electric current and two different electrodes 25 i. e., a grid and a plate, the second one (plate) is connected on the one hand, through a resistance to a source of current and, on the other hand, through a condenser, to the first electrode (grid) of the next audion; the first electrode of the first audion 30 being connected to the line.

The invention has for its object to complete installations of such kind by certain auxiliary connections having for their object to modify the amplifying.

It has been proposed in the patent application S. N. 174,633 to connect the plate of one audion to the grid of the same audion or to the grid of one of the preceding audions. 40 In that form it is however often very difficult to ensure a regular working; it is frequently interfered with by the fact that the connection being too strong, the apparatus comes by itself into a state of electric oscillations detected at the telephone in the form of various whistling noises.

According to the present invention a connection is established between the plate of one audion and that of one of the preceding 45 audions.

Apart from this main arrangement, the invention comprises other arrangements more fully described in the following.

In the accompanying drawings Figs. 1 to 3 show diagrammatically receiver stations 55 established according to the invention.

The installations shown in the drawings comprise a certain number of special audions $a^1, a^2, \dots, a^m, \dots, a^n$, each having a filament $a^{10}, a^{20}, \dots, a^{m0}, \dots, a^{n0}$, a first electrode (grid) $a^{100}, a^{200}, \dots, a^{m00}, \dots, a^{n00}$, and a second electrode (plate) $a^{1000}, a^{2000}, \dots, a^{m000}, \dots, a^{n000}$;

a source of electricity b (storage or primary batteries) intended to supply current 65 for heating the filaments $a^{10}, a^{20}, \dots$, which are connected in parallel to the terminal of the said source;

another source of electricity c , intended to produce the tension v in the plates $a^{1000}, a^{2000}, \dots$; one of the terminals of the said source being connected to the terminal of opposite polarity of the source of electricity b and to one of the receiver terminals e^1 of the installation and the other terminal of the 75 said source c being connected through resistances $d^1, d^2, \dots$ respectively to the plates of the audions.

In such installations the grid of each audion is connected through a condenser $f^2, f^3, \dots$ to the plate of the preceding audion; and the grid of the first audion is connected, if desired, through a condenser f^1 , to the second terminal e^2 of the installation; and in the connection between the plate a^{n000} of the last audion and the source of electricity c the resistance is replaced by a telephone apparatus g or the like.

Preferably such installations are completed in connecting the grid of each audion through a resistance $h^1, h^2, \dots, h^m, \dots, h^n$, to a potentiometer j connected across the terminals of a source of current k , one of the terminals of which is connected to the positive terminal of the source of current b , owing to 90 which the mean voltage of the grid can be fixed at a suitable value.

According to the invention the amplification obtained with such installations is modified by establishing a connection between the plate of one audion and that of one of the preceding audions.

The two plates which are connected together are suitably selected.

It is known that the variation of voltage 105 in the plate is of opposite sign with respect

to the variation of the grid of the same audion. In fact, in case of an increase of voltage of the grid a^{moo} , the intensity of the current passing in the plate a^{mooo} of the same audion increases and as the current passing in the plate of an audion a^m increases, the loss of potential increases in the corresponding resistance d^m and consequently the potential in the plate a^{mooo} decreases; this results in a corresponding decrease of the voltage of the grid of the next audion and so on; these variations being now negative and now positive, and generally speaking, alternately negative and positive.

Now if it is desired to increase the amplification of the installations the two plates to be connected together must have variations of voltage of the same sign, for instance the plates of two audions separated by a third one.

Contrariwise, if it is desired to reduce the amplifying the two plates to be connected together must have variations of voltage of opposite sign, for instance the plates of two consecutive audions.

This connection can be ensured, as well in telephony as in telegraphy either as shown in Fig. 1, by a capacity m , the two electrodes of which are respectively connected to the two plates of the two audions, or, as shown in Fig. 2, by a resistance n .

In a very general manner, the connection can be obtained as shown in Fig. 3, by connecting a variable point of the resistance d of one audion to another variable point of the resistance d^n of another audion with interposition in the connection of an adjustable resistance o and if necessary of a capacity p .

Several of these connections can exist jointly in one and the same apparatus.

Obviously the invention is not limited to the methods particularly indicated, but comprises on the contrary any modifications within the scope of the claims.

Having now particularly described and ascertained the nature of our said invention, we declare that what we claim is:

1. In a receiver station for telephone and wireless telegraphy, installations having a number of audions, each audion comprising a filament heated by an electric current and two different electrodes namely a grid and a plate, the plates of the respective audions being connected each through a resistance to one pole of a source of current of suitable voltage, the other pole of which is connected to one of the receiver terminals, the grid of the first audion being connected to the other receiver terminal, the grid of each of the other audions being connected through a condenser, to the plate of the respective preceding audion, and means for modifying the amplifying effect of the in-

stallation comprising a connection having 65 a suitable impedance, such connection being established between the plates of two suitably selected audions.

2. In a receiver station for telephone and wireless telegraphy, installations having a 70 number of audions, each audion comprising a filament heated by an electric current and two different electrodes namely a grid and a plate, the plates of the respective audions being connected, each through one resistance, 75 to one pole of a source of current of suitable voltage, the other pole of which is connected to one of the receiver terminals, the grid of the first audion being connected, on the one hand, to the other receiver terminal, and on 80 the other hand, through a resistance, to a fixed positive voltage point, and the grid of each of the other audions being, on the one hand, connected, each through a condenser, to the plate of the preceding audion, 85 and on the other hand, to said fixed positive voltage point through a resistance for each grid, and a connection having a suitable impedance, said connection being established between the plates of two suitably 90 selected audions.

3. In a receiver station for telephone and wireless telegraphy, installations having a 95 number of audions, each audion comprising a filament, heated by an electric current, and two different electrodes, namely a grid and a plate, the plates of the respective audions being connected, through a resistance for each plate, to one pole of a source of current of suitable voltage, the other pole 100 of which is connected to one of the receiver terminals, the grid of the first audion being connected, on the one hand, to the other receiver terminal and, on the other hand, through a resistance, to a fixed positive voltage point, the grids of the other audions being each connected, on the one hand, to said fixed positive voltage point, through a resistance established for each grid, and on the other hand, through a condenser, to the plate 110 of the preceding audion, and a connection comprising an adjustable resistance, said connection being established between the plates of two suitably selected audions.

4. In a receiver station for telephone and 115 wireless installations, having a number of audions, each audion comprising a filament heated by an electric current, and two different electrodes namely a grid and a plate, the plates of the respective audions being 120 connected, through a resistance for each plate, to one pole of a source of current of a suitable voltage, the other pole of which is connected to one of the receiver terminals, the grid of the first audion being connected, on the one hand, to the other receiver terminal, and on the other hand, through a resistance, to a fixed positive volt- 125

age point, the grids of the other audions being each connected, on the one hand, to said fixed positive voltage point, through a resistance established for each grid, and 5 on the other hand, through a condenser, to the plate of the preceding audion, and a connection comprising an adjustable resistance and a condenser established between the plates of two suitably selected audions.

10 In testimony whereof we have hereunto set

our hands in presence of subscribing witnesses.
